UNITED STATES PATENT OFFICE

146,438

DESIGN FOR A SHOE

Lester C. Tullgren, Minneapolis, Minn., assignor of one-half to Helen Moessner, Menomonee, Wis.

Application July 23, 1946, Serial No. 131,867

Term of patent 7 years

(Cl. D7—7)

To all whom it may concern:

Be it known that I, Lester C. Tullgren, a citizen of the United States, residing at Minneapolis, in the county of Hennepin and State of Minnesota, have invented a new, original, and ornamental Design for a Shoe, of which the following is a specification, reference being had to the accompanying drawing, forming part thereof.

I claim:

The ornamental design for a shoe, as shown.

LESTER C. TULLGREN.
